DESIGN FOR A SOCK

Favorina Avandoglio, New York, N. Y.

Application March 8, 1941, Serial No. 99,438

Term of patent 7 years

To all whom it may concern:

Be it known that I, Favorina Avandoglio, a citizen of the United States, residing at New York, in the county and State of New York, have invented a new, original, and ornamental Design for a Sock, of which the following is a specification, reference being had to the accompanying drawing, forming part thereof.

The figure is a plan view of a sock in its flattened condition, showing my new design.

My design for a sock is characterized by a substantially four-sided outline, the front of the sock running diagonally in a substantially straight line from the toe to the top of the sock, the heel portion bulging rearwardly.

I claim:

The ornamental design for a sock, substantially as shown and described.

FAVORINA AVANDOGLIO.
